Attorney.

UNITED STATES PATENT OFFICE.

GILBERT F. QUINN, O. REVERE, MASSACHUSETTS.

RUBBER HEEL.

1,341,383.

Specification of Letters Patent. Patented May 25, 1920.

Application filed May 10, 1918, Serial No. 233,666. Renewed April 7, 1920. Serial No. 372,271.

To all whom it may concern:

Be it known that I, GILBERT F. QUINN, a citizen of the United States, residing at Revere, in the county of Suffolk and State of Massachusetts, have invented a new and useful Rubber Heel, of which the following is a specification.

The object of my invention is to provide a rubber heel which can be securely attached to the shoe without the use of cement, and which will yet contain the desirable air cushion unimpaired in its function.

It is further my object to provide a rubber heel conforming to the standard thickness of rubber heels for men's shoes on its outer surface and having an additional raised central platform and beveled surface to take up extra wear, and to cause the heel to maintain a sightly appearance for a longer period.

In the accompanying drawings, illustrating my invention, Figure 1 shows the heel attached to a shoe; Fig. 2 is a top plan of my invention; Fig. 3 is a bottom plan of the same; Fig. 4 is a section on line 4—4 of Fig. 2; and Fig. 5 is a similar section of the heel attached to a shoe.

Like numerals designate like parts in the several views.

Referring to the accompanying drawings, I provide a rubber heel 3, having a substantial upturned rim 4 extending around the heel. This rim has an inside beveled surface 5 and an outside beveled surface 6, the two surfaces being beveled to an unequal degree but surface 6 being of greater length and bevel than surface 5. Beveled surfaces 5 and 6 converge outwardly, the outside rim face 3 being disposed at approximately right angles to the inner surface 5 so that after the heel is attached to the shoe, rim face 3 is in alinement with the side face of the heel, thereby obviating the usual practice of trimming the rubber heel; and surface 6, having a greater bevel than surface 5 which latter surface rests flat against the heel, presents a slanting surface to take up additional wear and is disposed at an angle corresponding approximately to that assumed by the foot as it strikes the ground in natural walk. The wear is taken up principally by the raised central platform 10. In the upper portion of the heel I provide a chamfered portion 7 to form an air cushion and thus increase the

resilience and decrease the amount of rubber used. Extending around chamfered portion 7 I provide a nail hole rim 8 having a flat face surface parallel with the surface of the heel of the shoe. I further provide a suitable number of nail holes 9 extending through the rim.

In use the nail hole rim 8 arrests the descent of the heel at the proper degree as its face is perfectly parallel with the surface of the heel of the shoe, and it thus eliminates the possibility of imperfect contact such as would cause the heel washer embedded in the heel to work up and down on the nails and eventually wear the nail-head through the washer.

The converged outside rim face 3 is shaped to cause the heel to show a side face in exact alinement with the side face of the shoe heel when it has been attached thereto, in consequence of the natural action or change of position of the rubber heel, resulting from the nailing operation, as shown in Fig. 5, thus saving much labor and waste of rubber from the customary "trimming process" of other rubber heels. The outside beveled surface 6 of the heel takes up extra wear before the outside lower edge line is worn down to an unsightly degree.

The outside platform 10 of my heel may carry designs or imprints, at option of the manufacturer.

What I claim is:

1. A heel having an inside air chamber, an upper beveled face, a lower beveled face, and a side face that flares outward, the beveled portion of the heel gradually decreasing in thickness toward the said side face.

2. A rubber heel having an inside air chamber, a nail hole rim surrounding said air chamber, and a substantial upturned portion encircling the nail hole rim, said upturned portion having faces shaped to converge outwardly, for the purposes described.

3. A rubber heel having a chamfered inner portion forming an unobstructed air cushion, a flat nail hole rim extending around said portion, a substantial upturned rim extending around the heel beyond the nail hole rim, the lower face of the upturned rim being beveled to a greater degree than the upper face, said lower face

being shaped to present a flat wearing surface as the heel strikes the ground in ordinary use, the bottom of the heel having a raised platform, in which the aforesaid 5 lower beveled face terminates.

4. A cushion heel comprising a body having a central portion flat upon its top and

bottom surfaces, the body between said central portion and the outer edges being inclined upwardly and outwardly, the inclination of the bottom surface being greater than that of the upper surface. 10

GILBERT F. QUINN.
